RELIEF, BY-PASS, AND CHECK VALVE

Application filed January 10, 1929. Serial No. 331,413.

This invention relates to a combination relief, by-pass and check valve and more particularly to a valve designed for controlling the flow of heavy fluid, such as tar or oil, adapted to be sprayed upon roads.

In order to provide a satisfactory surface for roads it is customary to spray upon them tar or oil from a tank mounted on a truck or wagon, the spraying being done by means of nozzles extending crosswise of the road. When heavy viscous material, such as tar, is used, the material in the tank is heated. The liquid is pumped from the tank to the nozzles by means of a suitable pumping mechanism mounted on the carrier and it is necessary to provide a safety valve to prevent excessive pressure, and it is also necessary to by-pass the oil back into the tank either when the maximum pressure is exceeded or under certain conditions along the highway, when it is desired to either shut off or cut down the flow of tar or oil from the nozzles. Excessive pressure is very apt to occur, because of the small nozzle apertures, and consequently a suitable relief valve is necessary.

Heretofore two forms have been used, one for manually by-passing the liquid back to the tank and the other for by-passing the liquid when the pressure exceeded the predetermined amount, this latter valve acting as a safety or relief valve.

It is the broad object of the present invention to provide a combined valve which acts as an automatic relief valve to by-pass the fluid to the tank in case of excessive pressure and which also may be manually operable to by-pass the liquid under the stated conditions of operation.

It is a further object to provide in the above combination a check valve which will prevent backward flow of liquid.

Other objects relate to details of construction whereby a simple and satisfactory valve for handling highly viscous substances is produced. These objects and their accomplishment will be apparent from the following description.

In the drawing:

Fig. 1 is a vertical section through the 50 valve.

Fig. 2 is a vertical section taken at right angles to the section shown in Fig. 1.

The valve comprises a casing 2 having an inlet passage 4 in the bottom thereof and an exit passage 6 in the side thereof. It will be understood, however, as the description proceeds, that these apertures may be otherwise placed while nevertheless retaining the advantages of the invention. A vertical bore in alignment with the intake opening 4 is defined by the inner edges of webs 8 which, as disclosed, are four in number and which provide between them passages for liquid entering the inlet and passing about the movable valve member 10, which is in the form of a piston and arranged to slide through the bore defined by the inner edges of the webs. At the bottom of the webs the bore is completely cylindrical, as shown in the figures at 12, so that the valve piston 10, when in this portion of the bore, completely closes the inlet. A cylindrical valve seat 14 of brass or the like, having a bevelled upper edge, is arranged to provide a seat for the valve member 10 upon the entrance of valve 10 into the portion 12 of the bore.

Arranged in axial alignment with the bore through which the valve member 10 moves and slidably mounted in the top of the casing through suitable packing means is a stem 16. This stem is threaded at 18 throughout the lower portion of its length and on the end thereof is threaded a nut 20 adapted to act as a stop to prevent movement of valve member 10 off that end, valve member 10 being slidably mounted on the stem over the lower threaded portion thereof. In order to maintain valve member 10 in engagement with nut 20, a spring 22 is provided which at its lower end bears against the valve member and at its upper end reacts against a disc 24 which is slidably on the stem and which is maintained in an adjusted position by a nut 26 which is held securely by a suitable lock nut.

By the arrangement shown, it will be seen that movement of valve member 10 independently of stem 16 to open the inlet is resisted by means of spring 22, while the whole valve assembly, consisting of stem 16, valve mem-

ber 10 and spring 22 and associated parts, is movable as a unit to open the inlet, the stem being movable through the packing means at the upper portion of the casing. It will be observed that even though seat 14 is absent, the valve would close the inlet, and it is sometimes desirable to eliminate this seat 14 and consequently a stop 27 to limit inward movement of the stem is provided.

10 The outward movement of stem 16 is limited by means of a cam groove 28 in which the end of the stem rides, which groove is formed in a lever 30 pivoted to the casing at 32, the cam groove 28 being eccentric with respect to the pivotal center 32. Movement is imparted to lever 30 through the medium of a link 34 connected at one end thereto and at its other end to a lever 36 pivoted at 38 to the casing and provided with a handle 40 which 15 may be manually operated. An arcuate segment 42 secured to the casing is provided with a series of apertures 44 in any of which a pin 46 may be placed to limit the downward movement of arm 40.

20 Assuming the parts to be in the position shown in Fig. 1, the least eccentric portion of groove 28 is in contact with stem 16 and valve member 10 is maintained in contact with seat 14, or at least within portion 12 of the bore in which it moves, under the tension of spring 22. In this position the inlet is accordingly closed, unless excessive pressure sufficient to compress the spring 22 acts upon valve member 10, raising the same beyond portion 12 of the bore so as to permit the escape of fluid between webs 8 and through exit 6. Provision may be readily made for by-passing of the fluid under various relief pressures by substituting different springs for spring 22, or by adjusting the tension of the spring by moving disc 24 upwardly or downwardly and holding the same in position by nuts 26.

25 If it is desired to permit by-passing of the fluid, pin 46 may be removed and handle 40 depressed, the pin 46 being placed in a suitable aperture 44. By such adjustment, a more eccentric portion of cam groove 28 is brought into alignment with the stem and consequently pressure below valve member 10 produces a rise of the valve assembly as a whole, thereby permitting fluid to pass the valve member 10.

30 If at any time, while the valve member is open, a reversal of pressure or flow occurs, either the assembly or valve member 10 will move downwardly into contact with seat 14 or within portion 12 of the bore, thus producing a check valve action to close inlet 4.

35 60 What we claim and desire to protect by Letters Patent is:

1. A valve comprising a casing having a passage therein, a valve member adapted to close the passage to prevent flow of fluid therethrough, a control member provided

with a stop, said valve member being movable relatively to the control member, means reacting between the control member and the valve member for yieldingly holding the valve member against the stop, said control member being movable through the medium of the said reacting means under fluid pressure exerted on the valve member, and means for limiting such movement of the control member.

2. A valve comprising a casing having a passage therein, a valve member adapted to close the passage to prevent flow of fluid therethrough, a control member provided with a stop, said valve member being movable relatively to the control member, means reacting between the control member and the valve member for yieldingly holding the valve member against the stop, said control member being movable through the medium of the said reacting means under fluid pressure exerted on the valve member, and means for limiting such movement of the control member, said valve member being movable independently of the control member to open the passage under excessive pressure.

3. A valve comprising a casing having a passage therein, a valve member adapted to close the passage to prevent flow of fluid therethrough, a control member provided with a stop, said valve member being movable relatively to the control member, means reacting between the control member and the valve member for yieldingly holding the valve member against the stop, said control member being movable through the medium of the said reacting means under fluid pressure exerted on the valve member, and means for limiting such movement of the control member, said valve member being free to close the passage independently of the position of said movement limiting means.

4. A valve comprising a casing having a passage therein, a valve member adapted to close the passage to prevent flow of fluid therethrough, a control member provided with a stop, said valve member being movable relatively to the control member, means reacting between the control member and the valve member for yieldingly holding the valve member against the stop, said control member being movable through the medium of the said reacting means under fluid pressure exerted on the valve member, and means for limiting such movement of the control member, said valve member being movable independently of the control member to open the passage under excessive pressure, and being free to close the passage independently of the position of said movement limiting means.

5. A valve comprising a casing having a passage therein, a valve member adapted to close the passage to prevent flow of fluid therethrough, a control member provided

5 with a stop, said valve member being movable relatively to the control member, means reacting between the control member and the valve member for yieldingly holding the valve member against the stop, said control member being movable through the medium of the said reacting means under fluid pressure exerted on the valve member, and means for limiting such movement of the control member, said movement limiting means being adjustable.

10 6. A valve comprising a casing having a passage therein, a valve member adapted to close the passage to prevent flow of fluid therethrough, a control member provided with a stop, said valve member being movable relatively to the control member, means reacting between the control member and the valve member for yieldingly holding the valve member against the stop, said control member being movable through the medium of the said reacting means under fluid pressure exerted on the valve member, said control member having a portion extending outside the casing, and adjustable means outside the casing for limiting movement of the control member under fluid pressure acting to open the valve member.

15 7. A valve comprising a casing having a passage therein, a valve member adapted to close the passage to prevent flow of fluid therethrough, a stem slidably mounted in the casing, a stop carried by the stem, said valve member being movable relatively to the stem, a spring reacting between the stem and the valve member for yieldingly holding the valve member against the stop, said stem being movable through the medium of the spring under fluid pressure exerted on the valve member, and means for limiting such movement of the stem.

20 8. A valve comprising a casing having a passage therein, a valve member adapted to close the passage to prevent flow of fluid therethrough, a stem slidably mounted in the casing, a stop carried by the stem, said valve member being movable relatively to the stem, a spring reacting between the stem and the valve member for yieldingly holding the valve member against the stop, said stem being movable through the medium of the spring under fluid pressure exerted on the valve member, and means for limiting such movement of the stem, said valve member being movable independently of the stem to open the passage under excessive pressure.

25 9. A valve comprising a casing having a passage therein, a valve member adapted to close the passage to prevent flow of fluid therethrough, a stem slidably mounted in the casing, a stop carried by the stem, said valve member being movable relatively to the stem, a spring reacting between the stem and the valve member for yieldingly holding the valve member against the stop, said stem be-

30 ing movable through the medium of the spring under fluid pressure exerted on the valve member, and means for limiting such movement of the stem, said valve member being free to close the passage independently of the position of said movement limiting means.

35 10. A valve comprising a casing having a passage therein, a valve member adapted to close the passage to prevent flow of fluid therethrough, a stem slidably mounted in the casing, a stop carried by the stem, said valve member being movable relatively to the stem, a spring reacting between the stem and the valve member for yieldingly holding the valve member against the stop, said stem being movable through the medium of the spring under fluid pressure exerted on the valve member, and means for limiting such movement of the stem, said valve member being movable independently of the stem to open the passage under excessive pressure, and being free to close the passage independently of the position of said movement limiting means.

40 11. A valve comprising a casing having a passage therein, a valve member adapted to close the passage to prevent flow of fluid therethrough, a stem slidably mounted in the casing, a stop carried by the stem, said valve member being movable relatively to the stem, a spring reacting between the stem and the valve member for yieldingly holding the valve member against the stop, said stem being movable through the medium of the spring under fluid pressure exerted on the valve member, and means for limiting such movement of the stem, said movement limiting means being adjustable.

45 12. A valve comprising a casing having a passage therein, a valve member adapted to close the passage to prevent flow of fluid therethrough, a stem slidably mounted in the casing and projecting therethrough, a stop carried by the stem within the casing, said valve member being movable relatively to the stem, a spring reacting between the stem and the valve member for yieldingly holding the valve member against the stop, said stem being movable outwardly through the medium of the spring under fluid pressure exerted on the valve member, and adjustable means for limiting outward movement of the stem.

50 In testimony of which invention, we have hereunto set our hands, at Kennett Square and Philadelphia, Penna., respectively, on the 22nd day of October, 1928 and 7th day of January, 1929, respectively.
